UNITED STATES PATENT OFFICE

JOSEPH F. JOSETT AND JOSIAH ROSS, OF BUFFALO, NEW YORK, ASSIGNEES
TO SAID JOSEPH F. JOSETT.

IMPROVEMENT IN PAPER-BAG MACHINES.

Specification forming part of Letters Patent No. 173,019, dated February 1, 1876; application filed
March 31, 1875.

To all whom it may concern:

Be it known that we, JOSEPH F. JOSETT and JOSIAH ROSS, both of the city of Buffalo, in the county of Erie and State of New York, have invented certain new and useful Improvements in Paper-Bag Machines, of which the following is a specification:

Our invention relates to certain improvements for forming the body or tubular part of the bag.

The first part of our invention consists in the combination of the severing rollers with an adjusting device, whereby the point at which the cutter may strike within the groove in the roller may be regulated, as will be more clearly hereinafter shown.

The second part of our invention consists in the combination of a vertically adjustable roller head or frame with the severing device and an adjustable gear-wheel, so that rollers of various sizes may be used.

The third part of our invention consists in the combination of the creasing-rollers and creasing-wheels, when made adjustable horizontally and vertically.

The fourth part of our invention consists of an adjustable forming-roller, made adjustable in the direction of its length, so as to answer for bags of different widths.

In the accompanying drawings, Figure 1 represents a side elevation of the machine complete; Fig. 2, a plan or top view of the same; Fig. 3, a side view of the severing-rollers, and Fig. 4 an end view.

A represents the frame of the machine; B, the paper-roll and roll of paper; C, the creasing-roller, over which the paper passes beneath the creasing-wheels D, which are made adjustable vertically, or nearly so, by means of the thumb screws and springs d, and horizontally on the shaft by means of the set-screws d'. E represents the adjustable forming-roller. It is made in two parts, one part consisting of a cylinder having a portion of smaller diameter, so as to allow the other portion—a sleeve or barrel—to slide over it like the tubes of a telescope, so that its length may be increased or shortened. It is adjusted and held when set to the length desired by means of the bolt or

set-screw f. f¹ represents the arms for holding it to the shaft f², upon which they are adjusted horizontally by the set-screws f³. The arms f¹ are arranged so as to slide in the parts f⁴, and allow the pressure of the roller on the paper to be regulated by means of the slots and set-screws g. G represents the two friction-rollers. They are held within the frame g¹, which is fastened by set-screws g² to the supports g³, so that the frame g¹ may be made to incline at an angle, more or less, from the horizontal line of the machine-bed, and thereby regulate the friction upon the paper as it is drawn through it by the feed-rollers H. h is a set-screw for regulating the pressure of said rollers. The feed-rollers are geared with the severing-rollers by means of the gearing T, U, V, W, and X. I and J are the severing-rollers. The lower one is set back of the upper one, as shown, so that the paper will lie close to it while the cutting device is separating it. K K are set-screws for regulating the distance of the severing-rollers from each other, and, consequently, their pressure on the paper. The upper roller I is provided with a serrated bar, i. j on roller J is a groove, into which the bar i strikes when dividing the paper. The point at which the bar i shall enter the groove j is regulated by the arm L, which is keyed rigidly to the shaft of roller I. The wheel X, being arranged to turn easily on said shaft, allows it to be connected to the arm L by means of a set-screw, M, passing through the slot m in said wheel, by which operation it is obvious the said adjustment may be made. N represents the vertically-adjustable frame for supporting the severing-rollers. It is connected to the frame A by the slide P, and is adjusted by the thumb-screw R. (Shown in dotted lines, Fig. 1.) The object of the frame N is to allow the use of rollers of different sizes. For large rollers its position would be lower than for small rollers. The wheel V is made movable, so that it can be adjusted and put into gear with the other wheels, so as to connect all together, when the position of the frame N is changed.

What we claim as our invention is as follows:

1. The combination of the rollers I J, arm L, set-screw M, and wheel X, arranged substantially as and for the purpose described.	4. The forming-roller E, consisting of three parts—a cylinder, sleeve, and set-screw, f—all combined and arranged substantially as and for the purposes described.
2. The combination of the frame N, severing-rollers I J, adjustable wheel V, and the frame-adjusting device R, as and for the purposes described.	
3. The adjustable creasing-wheels D, set-screws d d', in combination with the creasing-roller C, as and for the purposes specified.	

JOSEPH F. JOSETT.
JOSIAH ROSS.
